ENGINE-FLUSHING DEVICE.

Application filed February 6, 1924. Serial No. 691,054.

Our invention relates to and has for its purpose the provision of a flushing device adapted to be manually controlled by the operator of a motor vehicle and which utilizes the suction created in the intake manifold of an internal combustion engine to supply a sufficient quantity of suitable liquid to the engine of the motor vehicle for effecting the removal of carbon from the cylinders and valves of the engine.

It is also a purpose of our invention to provide a flushing device of the above described character having a measuring tank to which a carbon removing liquid is first supplied from a reservoir tank and subsequently discharged into the intake manifold of the engine, the passage of liquid from one tank to the other and its discharge into the manifold being manually controlled through the operation of a single valve element.

We will describe only one form of engine flushing device embodying our invention and will then point out the novel features thereof in claims.

In the accompanying drawings.

Figure 1 is a view showing in vertical section in one form of engine flushing device embodying our invention; and

Figure 2 is a transverse sectional view taken on the line 2—2 of Figure 1.

Referring specifically to the drawings, in which similar reference characters refer to similar parts, our invention in its present embodiment comprises a metallic base 15 of disk form and having its periphery provided with an upstanding annular flange 16 which is riveted or otherwise secured to a cylindrical metallic member 17 which constitutes the measuring tank of the device. The base 15 is provided axially thereof with a depending extension 18 provided with a duct 19 in communication with an elbow pipe 20 threaded into the extension and adapted for communication with the intake manifold of an internal combustion engine (not shown) through the medium of a pipe 21, detachably associated with the elbow by a connection 22. Extending from the upper side of the base 15 is an annular collar 23 internally threaded to receive a plug 24 having a frusto conical duct 25 reversely dis-

posed with respect to a similarly shaped duct 26 formed in the extension 18 and constituting a continuation of the duct 19. Between the conical ducts 25 and 26 an annular duct 27 is formed in the base which, at times, communicates with the interior of the measuring tank 17 through a discharge port 28.

The plug 24 provides a supporting means for a reservoir tank 29 arranged within the measuring tank 17 and having a frusto conical lower end provided with a flange 30 which is welded or otherwise secured to the plug 24. The plug is provided at its upper end with recesses 31 in which the prongs of a spanner wrench are adapted to engage for screwing or unscrewing the plug within the collar 23.

The upper ends of the tanks 17 and 29 are closed by a cover plate 32 detachably secured to an annulus 33 by means of screws 34. The annulus in turn is welded or otherwise secured to the measuring tank 17 and a packing ring 35 is preferably interposed between the annulus and cover plate, as shown. Extending axially through the cover plate is a rod 36 carrying at its lower end a valve element V preferably formed of cork and fixedly secured to the rod by means of nuts 37. The upper end of the rod extends exteriorly of the cover plate and has attached thereto a wire 38 or other flexible member which is adapted to extend through the dashboard of a motor vehicle or some other suitable point within easy reach of the operator of the vehicle. A spring 39 surrounds the rod and is interposed between the cover plate 32 and a collar 40 fixed to the rod whereby the rod, together with the valve element, is urged downwardly to the position shown in Figure 1. The valve element is reversely tapered to provide in reality two valves 41 and 42, the valve 41 being adapted to seat in the conical duct 25, while the valve 42 is adapted to seat within the conical duct 26.

As shown in Figure 1, the cover plate 32 is provided with a vent including a screw plug 43 having a vent opening 44 through which air may be supplied to the reservoir tank. Air may be supplied to the measuring tank 17 through a vent opening 45.

In practice, the pipe 21 is connected to

the intake manifold of an internal combustion engine between the engine and the carburetor. The reservoir tank is adapted to be filled with a suitable liquid which, when introduced into the cylinders of the engine, is adapted to loosen or dissolve the carbon particles adhering to the cylinder head, piston and valves, so that during the operation of the engine the carbon will be removed therefrom. With the valve element V in the position shown in Figure 1, the liquid in the reservoir tank 29 will flow into and fill the measuring tank 17 through the duct 25 and the port 28. This measuring tank 17 is designed to receive sufficient liquid for effectively flushing an engine to remove the carbon therefrom, and the liquid can be discharged from this measuring tank by pulling the rod 36 upwardly against the tension of the spring 39 to cause the valve element to occupy its uppermost position, wherein the duct 25 is closed by the valve 41, while the duct 42 is opened or placed into communication with the discharge port 28 so that the liquid in the tank can flow therefrom into the pipe 21 and finally into the intake manifold of the engine. As the liquid enters the intake manifold the suction created by the engine will operate to draw this liquid into the cylinders and thus effect removal of the carbon therefrom.

It will be noted that with the valve element in its uppermost position the discharge of liquid from the reservoir tank into the measuring tank is prevented, and consequently while the liquid is being discharged from the measuring tank no liquid will flow from the reservoir tank into the latter. However, as soon as the valve rod 36 is released the spring 39 functions to move the valve element to its lowermost position, wherein the valve 42 seats within the duct 26 to disconnect the port 28 from the duct. Simultaneously with this movement the valve 41 unseats the duct 25 and thus places the duct in communication with the port 28 so that liquid from the reservoir tank can flow therethrough into the measuring tank, whereupon the latter is again filled and the device ready for a second operation.

From the foregoing operation taken in conjunction with the accompanying drawing, it will be manifest that we have provided a device which can be manipulated by the operator of a motor vehicle to supply one or more charges of carbon removing liquid to the internal combustion engine while the latter is in operation and irrespective of whether the vehicle is under way or at a standstill, whereby those moving parts of the engine where carbon has a tendency to deposit can be kept free and clean. In this manner the accumulation of carbon on the valves and piston rings is prevented and their proper operation at all times insured.

Although we have herein shown and described only one form of engine flushing device embodying our invention, it is to be understood that various changes and modifications may be made herein without departing from the spirit of the invention and the spirit and scope of the appended claims. 70

What is claimed is:

1. An engine flushing device comprising a liquid reservoir tank, having a discharge port, a liquid measuring tank below the first tank and having a discharge port, a discharge pipe below the second tank, and a valve element movable to one extreme position in which the discharge ports are placed in communication with each other to permit liquid from the reservoir tank to flow into and fill the measuring tank, and another extreme position in which the discharge port of the reservoir is closed and the discharge port of the measuring tank placed in communication with the discharge pipe to allow the liquid in the measuring tank to flow into said pipe. 75

2. An engine flushing device as embodied in claim 2, wherein the valve element is normally urged to the first extreme position and adapted to be manually moved to the second extreme position. 80

3. An engine flushing device comprising a measuring tank, a reservoir tank within the measuring tank, a base for closing the lower end of the measuring tank, a discharge duct formed in the base, a second discharge duct in the base having communication with the reservoir tank, a discharge port in the base for placing the measuring tank in communication with either of the discharge ducts, and a valve element movable in the base to alternately close or open either of the discharge ducts whereby the discharge port is alternately placed into or out of communication with the discharge ducts. 95

4. An engine flushing device comprising a base, a measuring tank supported on the base, a depending extension on the base having a duct formed therein, an upstanding collar on the base, a plug removably fitted within the collar and having a duct therein, a reservoir tank supported on the plug and in communication with said duct, a port in the base between said ducts and providing communication with the measuring tank, and a valve element movable in the base in the manner and for the purpose described. 100

5. An engine flushing device comprising a base, a measuring tank supported on the base, a depending extension on the base having a duct formed therein, an upstanding collar on the base, a plug removably fitted within the collar and having a duct therein, a reservoir tank supported on the plug and in communication with said duct, a port in the base between said ducts and providing communication with the measuring tank, and 105

a valve element movable in the base and comprising a pair of valves, one for each of said ducts, a rod connected to the valves and extending exteriorly of the reservoir tank, means for urging the rod to a position in which the first duct is closed and the second in communication with said discharge port,

and manually operable means for moving the valves to a position in which the other valve closes the second duct and the first valve ¹⁰ opens the first duct to place the latter in communication with the discharge port.
